UNITED STATES PATENT OFFICE.

FRANK F. PAPA, OF BROOKLYN, NEW YORK.

DESIGN FOR A WAITING BOOTH OR THE LIKE.

Application filed February 20, 1929. Serial No. 30,153. Term of patent 14 years.

To all whom it may concern:

Be it known that I, FRANK F. PAPA, a citizen of the United States of America, residing at 541 Dahill Road, Brooklyn, N. Y., have invented a new, original, and ornamental Design for a Waiting Booth or the Like, of which the following is a specification, reference being had to the accompanying drawing, forming part thereof.

In the drawing:—

I claim:

The ornamental design for a waiting booth or the like substantially as shown.

FRANK F. PAPA
